US0D1082641S

(12) **United States Design Patent** (10) Patent No.: **US D1,082,641 S**
(45) Date of Patent: ** Jul. 8, 2025

(54) **VEHICLE WHEEL RIM**

(71) Applicant: **VOLKSWAGEN AKTIENGESELLSCHAFT**,
Wolfsburg (DE)

(72) Inventor: **Thomas Sittler**, Wolfsburg (DE)

(73) Assignee: **VOLKSWAGEN AKTIENGESELLSCHAFT**,
Wolfsburg (DE)

(**) Term: **15 Years**

(21) Appl. No.: **29/903,915**

(22) Filed: **Sep. 28, 2023**

(51) LOC (15) Cl. **12-16**

(52) U.S. Cl.

USPC **D12/209**

(57) **CLAIM**

The ornamental design for a vehicle wheel rim as shown and described.

DESCRIPTION

FIG. 1 is a front elevation view of the vehicle wheel rim showing the present design; and,

FIG. 2 is a front, side perspective view thereof.

The broken lines depict portions of the vehicle wheel rim that form no part of the claimed design.

1 Claim, 2 Drawing Sheets
